OF GLOUCESTER, MASSACHUSETTS.**

TELEDYNAMIC SYSTEM FOR GUIDE LIGHTS.

Application filed June 18, 1917. Serial No. 175,108. Renewed April 24, 1924.

To all whom it may concern:

Be it known that I, ALBERT D. TRENOR, a citizen of the United States, and a resident of the city, county, and State of New York, have invented certain new and useful Improvements in Teledynamic Systems for Guide Lights, of which the following is a specification.

Some of the objects of this invention are to provide an improved system for guide lights for movable bodies, whereby the lights may be controlled from a distance so as to furnish a guide visible always from a given point, and always invisible from other given points; to provide improved means for controlling guide lights from a distance; and to provide other improvements as will appear hereinafter.

In the accompanying drawings, Fig. 1 is a diagram partly in top plan view and partly in side elevation showing a system of guide lights constructed in accordance with this invention; Fig. 2 a fragmentary top plan view of a portion of the same; Fig. 3 a development of a commutator forming a part of the same; Fig. 4 a diagrammatic side elevation of a modified form of this invention; and Fig. 5 a top plan view of a portion of the same.

Referring to the drawings, one embodiment of this invention comprises four relatively fixed electric lights 10, 11, 12 and 13 (shown in top plan view in Fig. 1), which are preferably arranged in substantially the same horizontal plane, and to radiate from a common center located in the longitudinal axis of a substantially vertical post 14 to which the lights are secured. The lights 10 to 13 are preferably arranged symmetrically with respect to the post 14 and so that the angle between any two successive lights is approximately a right angle. The lights 10, 11, 12 and 13 are separated by four flat normally vertical opaque screens 16, 17, 18 and 19 which radiate from and are rigidly secured to the post 14, and which are symmetrically arranged with respect to the post 14 so that the angle between any two successive screens is about ninety degrees, and is bisected by the corresponding light 10, 11, 12 or 13. The post 14 is rigidly secured to a marine vessel or other movable body in such a manner that the post 14 will be normally vertical and will hold the lights 10, 11, 12

and 13 in such positions as to be visible in 55 turn from a given distant point.

For controlling the lights 10, 11, 12 and 13 so that only that light which faces nearest towards a predetermined point will be illuminated, a commutator 25 is rigidly secured to a normally vertical spindle 26 which is arranged to rotate about a normally vertical axis in a stationary sleeve or bearing 27. The commutator 25 is arranged to cooperate with five brushes 31, 32, 33, 34 and 35, one of which, 31, is connected by a conductor 36 to one pole of a battery 37, the other pole of which is connected by a conductor 38 with one terminal of each of the lights 10, 11, 12 and 13, the other terminals 70 of the lights being connected respectively by conductors 42, 43, 44 and 45 with the other four brushes 32, 33, 34 and 35 respectively. The commutator 25 includes a cylindrical core 46 of insulating material surrounding and secured to which is a hollow cylindrical continuous conductor 47, and four segmental conductors 48, 49, 50 and 51. The cylindrical conductor 47 is arranged to be engaged at all times by uppermost brush 80 31, and the four segmental conductors 48, 49, 50 and 51 are arranged to be engaged successively by the four lower brushes 32, 33, 34 and 35, only one of these lower brushes being in contact with its corresponding segment at any one time. The segments 48, 49, 50 and 51 extend throughout slightly less than a quarter of a circle, so that one of the brushes 32, 33, 34 and 35 leaves its segment just as the next brush comes into contact 90 with its segment. The four segments 48, 49, 50 and 51 are connected to each other and to the continuous contact 47 by means of a conductor 55 arranged within the insulating core 46. The arrangement is such 95 that as the commutator 25 is rotated in a given direction, the lights 10, 11, 12 and 13 will be successively illuminated through the action of the battery 37 controlled by the brushes 31 to 35.

For holding the commutator 25 normally against rotation about its longitudinal axis, a gyroscope 60 is provided having a normally vertical stem 61 which is held by the gyroscope 60 in a well known manner against rotation about its longitudinal axis. The stem 61 is held so that its longitudinal axis corresponds with the longitudinal axis of

the spindle 26, and is provided at its upper end with a yoke 62 rigid therewith in which loosely engages a plate or clutch member 63 which is rigidly secured to the lower end of a vertical piston rod 64 which is secured at its upper end to a piston 65 which is arranged to reciprocate vertically in a cylinder 66 which is rigid with the lower end of the spindle 26. The lower end of the cylinder 66 is provided with an internal annular flange 67 and a spiral spring 68 which is normally compressed between the piston and the flange 67 and forces the piston 65 upwardly so as to cause the plate 63 to clamp the yoke 62 against the lower end of the cylinder 66, thus causing the commutator 25 to be controlled by the gyroscope 60.

For releasing the commutator 25 from the gyroscope 60, and at the same time resetting the commutator 25 independently of the gyroscope 60, an axial passage 70 leads upwardly from the upper end of the cylinder 66 and communicates at all times through an annular recess 71 in the surface of the spindle 26 with an air supply pipe 75 which communicates with a branch pipe 76 which communicates with the inner end of a normally horizontal stationary cylinder 77. Within the cylinder 77 is a piston 78 which is secured to the inner end of a piston rod 79, the outer end of which has rigidly secured thereto a horizontal transverse bar 80 which is arranged to reciprocate into and out of engagement with two cylindrical diametrically opposed pins or rollers 81 and 82 which are secured to the upper end of the core 46 of the commutator 25. The piston 78 is normally pressed inwardly by a spiral spring 83, and the piston rod 79 is held against rotation in any suitable manner, as for instance, by a pin 84 engaging in a keyway 85' provided therefor in the piston rod. The outer end of the cylinder 77 is closed by a head 86' which is imperforate except for a small opening 87 which is provided to permit the air to be forced only slowly out of the cylinder 77 by the piston 78 to retard the action of the piston 78 and thus prevent a too sudden movement of the crossbar 80 against the rollers 81, 82.

The resetting of the commutator 25 from a distance may be accomplished by controlling the inlet pipe 75 in any suitable manner from a distant station, but in the form of this invention shown the inlet pipe 75 is arranged to be controlled by a rotary valve 85 which is arranged in a stationary valve casing 86, the valve 85 and the valve casing 86 being constructed and arranged to be controlled in response to electroradiant energy and to control in any well known or suitable manner the movements of the movable body, and to control various functioning devices upon the boat, as shown for

instance, in my copending application, Serial No. 58,595.

In the form shown, the valve 85 is arranged to be rotated step by step in one direction through ninety degrees at each 70 step, as a result of the action of a piston 90 arranged in a stationary cylinder 91, and controlled by a reciprocatory valve 92 which controls the admission of air into the cylinder 91, from a pipe 93, leading from a stationary tank 94, or other supply of compressed air, the valve 92 also controlling the exhaust of air from the cylinder 91.

For supplying air to the pipe 75 and branch pipe 76 to operate the resetting mechanism, a pipe 95 leads from a point in the cylinder 91 suitably spaced between the limits of travel of the piston 90 to an inlet provided therefor in the valve casing 86 which is opposite the outlet from the valve 85 casing 86 into the pipe 75. A suitable diametrically arranged port 96 extends transversely through the valve 85 so that when the valve 85 is in a suitable position, communication will be established through 90 the valve from the pipe 95 into the pipe 75. The valve 85 is also provided with two diametrically opposed longitudinally extending recesses 97 and 98, which are arranged to act alternately to place the pipe 95 75 into communication with an outlet 99 provided therefor in the valve casing 86 when the valve 85 is arranged either as shown in the drawing or in a position 180 degrees therefrom and to close communication between the pipes 95 and 75. The inlet from the cylinder 91 into the pipe 95 is so arranged that when the piston 90 is in its outermost position towards the left, communication will be established from 105 the tank 94, through the pipe 93, cylinder 91 and into the pipe 95, and when the valve 85 is in proper position, the air will be permitted to flow from the tank 94 through the valve 85 into pipe 75 and branch pipe 110 76, and if the piston 90 is permitted to remain for a sufficient length of time in its outermost position and in advance of the inlet into the pipe 95, the piston 65 of the gyroscope clutch will be forced downwardly 115 and disconnect the commutator 25 from the gyroscope stem 61, and immediately thereafter the crossbar 80 will be moved into engagement with the rollers 81 and 82, and thus reset the commutator 25 with respect 120 to the gyroscope 60.

The valve 92 is controlled by a solenoid 100 which is in series with a normally open circuit including a battery 101 or other source of electric energy, and a normally open switch 102. The switch 102 is controlled by an electromagnet 103 which is in a circuit controlled by any suitable detector 104 which is arranged in a well known manner to be controlled by a closed oscillatory 130

circuit including a variable condenser 105 and an inductance 106, which forms the secondary of a transformer 107 which has a primary coil 108 which is arranged in series with an open aerial circuit or antenna 109 which is grounded as at 110.

In the operation of the system just described, the lights 10, 11, 12 and 13 are normally controlled by the gyroscope 60, 10 acting through the commutator 25, in such a manner that only the light which happens to be facing nearest to a predetermined direction will be illuminated at any given time. When it is desired to reset the commutator 25, the valve 85 is rotated from the position shown in Fig. 1 through 90 degrees, by transmitting a suitable impulse of electroradiant energy to cause the energization of the antenna 109, and the consequent closing of the switch 102 and energization of the solenoid 100. This impulse is prolonged to cause the valve 92 to be held in an open position, and to cause the piston 90 to be held in its outermost 20 position upon the left of the inlet to the pipe 95 for such a period of time that the air is permitted to pass from the tank 94 through the valve 85 and pipes 75 and 76 for a sufficient period to disconnect the commutator 25 from the gyroscope stem 61, and to cause the piston 78 to move the transverse bar 80 into engagement with the rollers 81 and 82 to rotate the commutator 25 with respect to the gyroscope stem 61. The impulse of electroradiant energy which has caused this operation is then discontinued, and this permits the valve 92 to be returned to a closed position, thus opening the exhaust of the cylinder 91 and allowing the 30 piston 90 to be returned to its innermost position under the action of the spiral spring provided in the cylinder 91 for this purpose. This closes the inlet into the pipe 95. A second impulse of electroradiant energy is then transmitted to reenergize the antenna 109 and to rotate the valve 85 through one step which causes one of the longitudinal recesses 97 or 98 to be brought into a position to permit the pipe 75 to 40 connect with the outlet 99, and thus permit the piston 78 to return to its initial position to release the transverse bar 80 from engagement with the rollers 81 and 82, and thus free the commutator 25 for its usual 50 operation, and at the same time permitting piston 65 to be moved upwardly under the action of the spiral spring 68 to clamp the commutator 25 into engagement with the gyroscope stem 61 to permit the commutator 25 to be controlled by the gyroscope 60.

The lights 10, 11, 12 and 13 are preferably arranged so that two of the lights 11 and 13 are in a line substantially parallel 60 with the longitudinal axis of the boat or

other movable body, and it is to be understood that when the boat is away from an observation point in a straight line extending through that point, the commutator 25 will be so adjusted with respect to the gyroscope 60 that only the light, for instance, the light 13, facing towards the observation point will be illuminated. If now the boat should turn towards the right through 90 degrees, only the next succeeding lamp 75 12 will be illuminated, and a further turn of the boat to the right through 90 degrees would cause only the lamp 11 to be illuminated. Suppose, however, that after the boat had proceeded a short distance toward the east from a given observation point, and then should turn towards the right through 90 degrees, and then proceed due south with only the corresponding lamp 12 illuminated, it is evident that after the boat had proceeded due south for a considerable distance, the illuminated lamp 12 would no longer be visible from the observation point, and it would now be necessary to readjust the commutator 25 with 80 respect to the gyroscope 60 so that the corresponding lamp, for instance, the lamp 13 would be illuminated. This would be done by turning the boat, if necessary, so that the boat would be proceeding away from the observation point along a line extending through the observation point and while thus proceeding a suitable prolonged signal would be transmitted to energize the antenna 109 and to effect the proper adjustment of the commutator 25 with respect to the gyroscope 60. After making this adjustment, an impulse of electroradiant energy would be transmitted to turn the valve 85 again through 90 degrees so as to release the commutator and to cause the commutator to be clutched to the gyroscope stem 61, as hereinbefore described. This would cause the rear light 13 to be illuminated 90 while the boat is proceeding upon a course due east or within an angle of 45 degrees in either direction from that course, and the lamp 13 will thus serve as a guide visible from the observation point under consideration. 100

In the modified form of this invention shown in Fig. 4, the construction may be the same as that shown in Figs. 1 and 2, and just described, except that instead of the commutator 25 and the plurality of lamps 10, 11, 12 and 13 arranged to be controlled thereby, a gear 150 is secured to the upper end of the spindle 26, and is arranged coaxially therewith. Two diametrically opposed pins or rollers 151 corresponding to the rollers 81 and 82 of Figs. 1 and 2 are secured upon the upper surface of the gear 150 and are arranged to be engaged by the transverse bar 80, as hereinbefore described. The gear 150 is arranged to 110 120 130

actuate a pinion 154 which is arranged to actuate an electrical transmitting device 155 which is held as a whole in a stationary position with respect to the stationary bearing or sleeve 27. The electrical transmitter 155 is connected by a four wire cable 156 to an electrical repeating device 157, the cable 156 including a return wire 158 having in series therewith a battery 159 or other 10 source of electrical energy. The electrical repeater 157 is mounted upon a stationary platform 158 and is arranged to rotate a pinion 159 which engages a gear 160 which is rigidly secured to a vertical spindle 161 15 which extends upwardly from the platform 158 and which is arranged in stationary bearings 162 and 163 to rotate about a fixed vertical axis. Upon the upper end of the spindle 161 is rigidly secured an opaque 20 reflector 165 which may be parabolic in form or of any other suitable form, in which is arranged an electric lamp 166 which is energized by a stationary battery 167 acting through a commutator 168 and insulated 25 conductors 169 extending from the commutator upwardly through the spindle 161. A cylindrical glass or other transparent casing 170 may be mounted upon the platform 158 to surround the lamp 166 and other parts carried by the platform, and this casing may 30 be provided with a suitable top or cover 171 impervious to water to protect the parts carried by the platform 158.

In the operation of this modified form 35 of the invention, the reflector 165 and the lamp 166 carried thereby are normally caused to face in a given direction by the gyroscope 60 acting through the electrical transmitter 156 and electrical repeater 157. 40 The reflector 165 and the lamp 166 may be readjusted with respect to the gyroscope 60 by a prolonged impulse of electroradiant energy acting upon the antenna 109, to disconnect the spindle 26 from the gyroscope 45 to force the transverse bar slowly into engagement with the rollers 151, as herein-before described. When the transverse bar 50 is thus moved slowly into engagement with the rollers 151, the gear 150 is consequently rotated slowly to actuate the electrical transmitter 155 which causes the electrical repeater 157 to rotate the shaft 161 and the reflector 165 carried thereby with 55 respect to the gyroscope 60 to cause the reflector 165 to face in a direction parallel to the longitudinal axis of the boat or other movable body, and towards the point of observation when the boat is proceeding upon a straight line radiating from the 60 point of observation.

Although only two of the various forms in which this invention may be embodied have been shown herein, it is to be understood that this invention is not limited to 65 any specific construction, but might be em-

bodied in various systems without departing from the spirit of the invention or the scope of the appended claims.

Having thus fully described this invention, I claim:

1. The combination with a movable body, 70 of visible guiding means carried by said body for determining the position of said body from a given observation point, and means controlled from a distance for moving 75 said guiding means with respect to an axis of said body to cause said guiding means to be constantly directed toward said observation point.

2. The combination with a movable body, 80 of guiding means carried by said body for determining the position of said body from a given observation point, direction maintaining means carried by said body and arranged to control said guiding means, and 85 means controlled from a distance and operating independently of said direction maintaining means for modifying the visibility of said guiding means.

3. The combination with a movable body, 90 of luminous guiding means carried by said body for determining the position of said body from a given observation point, direction maintaining means carried by said body and arranged to control said luminous guiding means, and means controlled from a distance and operating independently of said direction maintaining means for modifying the visibility of said luminous guiding 95 means.

4. The combination with a movable body, 100 of guiding means carried by said body for determining the position of said body from a given observation point, a gyroscope carried by said body and arranged to control 105 said guiding means, and means controlled from a distance and operating independently of said gyroscope for modifying the visibility of said guiding means.

5. The combination with a movable body, 110 of guiding means carried by said body for determining the position of said body from a given observation point, a gyroscope carried by said body and arranged to control 115 said guiding means, and means controlled from a distance and operating independently of said gyroscope for modifying the action of said direction maintaining means upon said guiding means.

6. The combination with a movable body, 120 of luminous guiding means carried by said body for determining the position of said body from a given observation point, a gyroscope carried by said body and arranged to control 125 said luminous guiding means, and means controlled from a distance and operating independently of said gyroscope for modifying the visibility of said luminous guiding means.

7. The combination with a movable body, 130

of luminous guiding means carried by said body for determining the position of said body from a given observation point, a gyroscope carried by said body and arranged to control said luminous guiding means, and means controlled from a distance and operating independently of said gyroscope for modifying the action of said direction maintaining means upon said luminous guiding means.

8. The combination with a movable body, of visible guiding means carried by said body for determining the position of said body from a given observation point, and means responsive to radiant energy for moving said guiding means with respect to an axis of said body to cause said guiding means to be constantly directed toward said observation point.

9. The combination with a movable body, of guiding means carried by said body for determining the position of said body from a given observation point, direction maintaining means carried by said body and arranged to control said guiding means, and means responsive to radiant energy and operating independently of said direction maintaining means for modifying the visibility of said guiding means.

10. The combination with a movable body, of luminous guiding means carried by said body for determining the position of said body from a given point, and means responsive to radiant energy for moving said luminous guiding means with respect to an axis of said body to cause said guiding means to be constantly directed toward said observation point.

11. The combination with a movable body, of luminous guiding means carried by said body for determining the position of said body from a given observation point, direction maintaining means carried by said body and arranged to control said luminous guiding means, and means responsive to radiant energy and operating independently of said direction maintaining means for modifying the visibility of said luminous guiding means.

12. The combination with a movable body, of guiding means carried by said body for determining the position of said body from a given point, direction maintaining means carried by said body and arranged to control said guiding means, and means controlled from a distance for adjusting said guiding means with respect to said direction maintaining means.

13. The combination with a movable body, of guiding means carried by said body for determining the position of said body from a given point, direction maintaining means carried by said body and arranged to control said guiding means, and means controlled from a distance for rotatably adjusting said

guiding means with respect to said direction maintaining means.

14. The combination with a movable body, of luminous guiding means carried by said body for determining the position of said body from a given point, direction maintaining means carried by said body and arranged to control said guiding means, and means controlled from a distance for adjusting said guiding means with respect to said direction maintaining means.

15. The combination with a movable body, of luminous guiding means carried by said body for determining the position of said body from a given point, direction maintaining means carried by said body and arranged to control said guiding means, and means controlled from a distance for rotatably adjusting said guiding means with respect to said direction maintaining means.

16. The combination with a movable body, of guiding means carried by said body for determining the position of said body from a given point, a gyroscope carried by said body and arranged to control said guiding means, and means controlled from a distance for adjusting said guiding means with respect to said gyroscope.

17. The combination with a movable body, of luminous guiding means carried by said body for determining the position of said body from a given point, a gyroscope carried by said body and arranged to control said guiding means, and means controlled from a distance for adjusting said guiding means with respect to said gyroscope.

18. The combination with a movable body, of luminous guiding means carried by said body for determining the position of said body from a given point, a gyroscope carried by said body and arranged to control said guiding means, and means controlled from a distance for rotatably adjusting said guiding means with respect to said gyroscope.

19. The combination with a movable body, luminous guiding means carried by said body for determining the position of said body from a given point, direction maintaining means carried by said body and normally arranged to control said guiding means, and means controlled from a distance for temporarily interrupting the control of said guiding means by said direction maintaining means and adjusting said guiding means with respect to said direction maintaining means.

20. The combination with a movable body, luminous guiding means carried by said body for determining the position of said body from a given point, direction maintaining means carried by said body and normally arranged to control said guiding means, and means controlled from a distance for temporarily interrupting the control of

said guiding means by said direction maintaining means and rotatably adjusting said guiding means with respect to said direction maintaining means.

5 21. The combination with a movable body, of a rotatable member movable with respect to said body for emitting radiant energy in substantially a single direction from said body, and means independent of the movement of said body for controlling said member.

15 22. The combination with a movable body, of a rotatable member movable with respect to said body for emitting radiant energy in substantially a single direction from said body, and means independent of the movement of said body for rotating said member.

20 23. The combination with a movable body, of a rotatable member movable with respect to said body for emitting radiant energy in substantially a single direction from said body, and gyroscopic means independent of the movement of said body for rotating said member.

25 24. The combination with a movable body, of a rotatable member movable with respect to said body for emitting radiant energy in substantially a single direction from said body, and means including a gyroscope independent of the movement of said body for rotating said member.

30 25. The combination with a movable body, of means for emitting radiant energy from

said body in substantially a single direction, automatic direction maintaining means for controlling said first named means, and means independent of said automatic means for modifying the control of said first named means.

35 26. The combination with a movable body, of means for emitting radiant energy from said body in substantially a single direction, automatic direction maintaining means for controlling said first named means, and means at the will of an operator for modifying the control of said first named means.

40 27. The combination with a movable body, of means for emitting radiant energy from said body in substantially a single direction, automatic direction maintaining means including a gyroscope for controlling said first named means, and means controlled by radiant energy for modifying the control of said first named means.

45 28. The combination with a movable body, of means for emitting radiant energy in a given direction, means including a gyroscope for controlling said first named means, and manual means independent of said gyroscope for modifying the control of said first named means.

50 Signed at New York in the county of New York and State of New York this 11th day of June A. D. 1917.

ALBERT D. TRENOR.
